UNITED STATES PATENT OFFICE.

WILLIAM CHRISTENSEN, OF PHILADELPHIA, PENNSYLVANIA.

RHEOSTAT.

SPECIFICATION forming part of Letters Patent No. 776,454, dated November 29, 1904.

Application filed August 24, 1903. Serial No. 170,576. (No model.)

To all whom it may concern:

Be it known that I, WILLIAM CHRISTENSEN, a citizen of the United States, residing at Philadelphia, in the county of Philadelphia and State of Pennsylvania, have invented certain new and useful Improvements in Rheostats, of which the following is a specification.

This invention relates to rheostats or controllers; and it has for its object to provide a structure in which simplicity and durability of construction are combined with ease and efficiency of operation.

The invention consists in the novel construction and combinations of parts, which will be hereinafter fully described and claimed.

In the drawings, Figure 1 is an elevation of my improved rheostat, including in diagram an electric circuit connected thereto. Fig. 2 is a transverse section as on the line 2 2 of Fig. 1. Fig. 3 is a longitudinal section as on the line 3 3 of Fig. 1. Fig. 4 is a view of several of the resistance-coils as detached from the rheostat.

1 designates a hollow core or section of pipe, 25 and 4 a series of resistance-coils insulated therefrom and arranged thereon at intervals apart. In the present instance the coils 4 are formed of a continuous tape of resistance material, and the convolutions of the respective 30 coils are separated from each other and from the core 1 by a tape of insulating material 5 wound into the coils with the tape of resistance material.

The method of winding the coils 4 upon the 35 central core 1 is as follows: Starting at one end of the series, the tape is wound around the core 1 with the interposed insulating-tape 5 until a sufficient thickness has been wound to produce the first resistance-coil 4. The resistance-tape is then folded parallel to the core 1, and a slight distance from the first coil the resistance-tape is again folded at right angles to the core 1 and again wound around the core 1 with the interposed insulating-tape 5 until a sufficient thickness has been wound to 45 produce the second resistance-coil 4, and so on. The tape is folded, and each coil 4 is wound upon the core 1 until the entire series is produced. After the resistance-coils 4 have been 50 wound upon the core 1, as just described, each

coil 4 is secured in place by a contact-clip 6, clamped upon the outside convolution of its coil 4. This contact-clip 6 in its preferred form comprises a split ring 7, provided with two outwardly-projecting contact-blades 8 55 and drawn together by the action of a suitable bolt 9 to clamp its coil 4 in place. The ring 7 is also provided with a projection 10, into which is screwed a binding-post 11, by means of which the clip may be connected to an electric circuit. The uppermost clip 6 (shown in Fig. 1) is mounted on an insulating-collar 12 on the core 1, is connected directly to the end of the resistance-tape, and is not provided with a resistance-coil 4, and the lowermost 65 clip 6 (shown in Fig. 1) is mounted on an insulating-collar 20 on the core 1, is not provided with a resistance-coil 4, and is not connected to the resistance-tape.

Secured to the core 1, near one end of the 70 series of resistance-coils 4, is a collar 13, provided with a projecting arm 14, to the outer end of which is pivoted one end of a connecting-arm 15, arranged in line with the space between the blades. This connecting-arm 15 75 extends along the series of contact-clips 6 and is movable successively into and from engagement therewith—that is to say, as the arm is moved inwardly toward the core 1 said arm will pass successively between and into engagement with the pairs of blades 8 of the clips 6, engaged with the series of resistance-coils, and as the arm 15 is moved outwardly away from the core 1 said arm will be moved successively from between and into engagement with the said pairs of blades 8. The free end of the connecting-arm 15 extends freely through a suitable guiding-arm 16, projecting from a collar 17, secured to the core 1, and the free end of the arm 15 is provided 80 with a handle 18, by means of which it may be operated. The handle 18 may be insulated from the arm 15 in any suitable manner.

When the above-described rheostat is arranged in an electric circuit—such, for example, as is illustrated in Fig. 1 and designated 95 19—the operation is as follows: When the connecting-arm 15 occupies its innermost position, the electric current will flow through said arm and the two contact-clips 6 at the 100

respective ends of the series of resistance-coils 4 and be unaffected by the rheostat. When the arm 15 is moved outwardly to disengage it from the blades 8 of the first contact-clip 6 at the top of the series, the current will flow through the first resistance-coil 4, thence through the second clip and arm 15, and out through the lowermost contact-clip 6. When the arm 15 is moved outwardly to disengage it from the blades 8 of the second clip 6, the current will then flow through the two coils at the top of the series and out through the third clip 6, the arm 15, and the lowermost clip 6, and so on. As the arm 15 is moved outwardly the resistance-coils 4 will be successively cut into the circuit, and when the arm 15 passes from engagement with the second clip 6 above the collar 13, or the last clip engaged with the resistance-tape, the electric circuit will be broken. Thus it will be seen that by moving the arm 15 in and out any number of the resistance-coils 4 may be cut into or cut out of the circuit as desired, and by moving the arm 15 to its outermost position the circuit may be broken.

One of the principal features of my invention is the hollow central core 1, common to all the resistance-coils. By reason of this feature the entire series of resistance-coils 4 may be kept cool by a current of air or water passing through the core 1. When water is employed and heated by passing through the rheostat, the hot water may be utilized for various purposes, or it may be caused to flow through a coil of pipe and used for heating purposes.

I claim—

1. In a rheostat, or controller, a central core, a resistance arranged upon said core and comprising a single continuous strip spirally wound to form a series of coils, the portions of the strip between the coils being folded to provide intermediate connections between the coils, and means for cutting said coils into and out of an electric circuit.

2. In a rheostat, or controller, a central core, a series of resistance-coils mounted thereon and insulated therefrom, contact-clips surrounding said coils and holding the latter upon the core, and a movable contact member adapted to be moved successively into or out of engagement with said contact-clips, substantially as described.

3. In a rheostat, or controller, a series of resistance-coils, contact-clips surrounding said coils and holding the latter upon the core, and a pivoted contact-arm adapted to be moved successively into or out of engagement with said contact-clips, said arm being so arranged as to maintain its engagement with each successive contact-clip until the entire series of clips have been engaged therewith, substantially as described.

4. In a rheostat, or controller, a central core, a series of resistance-coils mounted thereon,

contact-clips surrounding said coils and holding the latter upon the core, and a contact-arm pivoted to move toward and from said core, said arm being so arranged as to maintain its engagement with each successive contact-clip until the entire series of clips have been engaged therewith, substantially as described. 70

5. In a rheostat, or controller, a central core, a series of resistance-coils mounted thereon, contact-clips surrounding said coils and holding the latter upon the core, and a contact-arm pivotally connected to said core and adapted to be moved successively into or out of engagement with said contact-clips, substantially as described. 80

6. In a rheostat, or controller, a central core, a resistance-coil mounted thereon, a contact-clip surrounding said coil and provided with contact-blades said clips holding the coils upon the core, and a movable contact member adapted to be moved into and out of engagement with said blades, substantially as described. 85

7. In a rheostat, or controller, a central core, a resistance-coil mounted thereon, a split ring surrounding said coil, means for drawing said ring together to clamp the coil, contact-blades projecting from said ring, and a movable contact member adapted to be moved into and out of engagement with said blades, substantially as described. 90

8. In a rheostat, or controller, a central core, a resistance arranged upon said core and comprising a single continuous strip spirally wound to form a series of coils, the portion of the strip between the coils being folded to provide intermediate connections between the coils, contact-clips surrounding said coils and holding the latter upon the core, said clips having contact-blades, and a movable contact member adapted to be moved into and out of engagement with the blades of said clips. 100

9. In a rheostat, or controller, a central core, a resistance arranged upon said core and comprising a single continuous strip spirally wound to form a series of coils, the portion of the strip between the coils being folded to provide intermediate connections between the coils, split rings surrounding said coils and holding the latter upon the core, said rings having contact-blades arranged in alinement with each other, and a movable contact member adapted to be moved into and out of engagement with the blades of said clips. 110

10. In a rheostat, or controller, a central core, a resistance arranged upon said core and comprising a single continuous strip spirally wound to form a series of coils, the portion of the strip between the coils being folded to provide intermediate connections between the coils, split rings surrounding said coils and holding the latter upon the core, said rings having contact-blades arranged in alinement with each other, and a contact member pivoted adjacent to said blades and adapted to be 120 125 130

moved into and out of engagement therewith for successively cutting in and out the respective coils.

11. In a rheostat, or controller, a central core, a resistance arranged upon said core and comprising a single continuous strip spirally wound to form a series of coils, the portion of the strip between the coils being folded to provide intermediate connections between the coils, split rings surrounding said coils and holding the latter upon the core, said rings having contact-blades arranged in alinement with each other, a movable contact member adapted to be moved into and out of engagement with the blades of said clips, and means for guiding said contact member in its movement.
12. In a rheostat, or controller, a central core, a resistance arranged upon said core and

comprising a single continuous strip spirally wound to form a series of coils, the portion of the strip between the coils being folded to provide intermediate connections between the coils, split rings surrounding said coils and holding the latter upon the core, said rings having contact-blades arranged in alinement with each other, a movable contact member adapted to be moved into and out of engagement with the blades of said clips, and a guiding-arm through which the contact member projects, whereby the latter is guided in its movements.

In testimony whereof I affix my signature in presence of two witnesses.

WILLIAM CHRISTENSEN.
